ELECTRIC SNAP SWITCH

George J. Meuer, Milwaukee, Wis., assignor to
 Cutler-Hammer, Inc., Milwaukee, Wis., a corporation of Delaware

Application May 22, 1939, Serial No. 274,872

17 Claims. (Cl. 200—16)

This invention relates to improvements in electric snap switches, and more particularly to switches of the tool-handle type.

A primary object of the invention is to provide an improved form of tool-handle switch of the double-pole, double-throw type without an "off" position.

Another object is to provide a switch of the aforementioned character having parts of rugged and durable construction, and which is not likely to get out of order.

Another object is to provide such a switch with stationary and movable contact elements of improved form.

Another object is to provide a double-pole, double-throw snap switch of substantially dust-tight construction.

Another object is to minimize the number of different parts required to produce a switch of the aforementioned character.

Another object is to provide a novel form and assembly of insulating carrier and bridging contactors for electric snap switches of the aforementioned character.

Another object is to provide a switch having a novel arrangement of six wiring terminal members at a common level adjacent to the upper surface of the base.

Other objects and advantages of the invention will hereinafter appear.

The accompanying drawings illustrate certain embodiments of the invention which will now be described, it being understood that the embodiments illustrated are susceptible of modification in respect of certain details of construction thereof without departing from the spirit and scope of my invention as defined by the appended claims.

In the drawings, Figure 1 is a longitudinal vertical section through a double-pole, double-throw snap switch constructed in accordance with my invention, the opposite end portions of the base being shown in elevation.

Fig. 2 is a top plan view of the insulating base shown in Fig. 1, with the stationary and movable contact elements in position, one of the upper stationary contact elements being broken away to better illustrate the cooperative relationship of the bridging contactors.

Fig. 3 is an end elevation of the switch shown in Figs. 1 and 2.

Fig. 4 is a section on the line 4—4 of Fig. 2, the relatively thin insulating plate being shown in assembled relation to the upper pair of resilient stationary contacts.

Fig. 5 is a perspective view of the insulating carrier for the contactors, one of the contactors being shown in assembled position and the other contactor being shown in separated relation.

Fig. 6 is a perspective view of a fragment of the insulating base showing the manner in which the insulating base is notched and recessed from the upper and outer surfaces of each longitudinal side wall thereof to accommodate the wiring terminal elements of the upper pair of resilient contactors.

Fig. 7 is a longitudinal sectional view similar to Fig. 4, but showing modified forms of stationary contacts, contactors and insulating carrier for the latter, and

Fig. 8 is a perspective view of the insulating carrier shown in Fig. 7, one of the contactors being shown in assembled position and the other contactor being shown in separated relation.

20 The switches herein disclosed are in certain respects like those described and claimed in my patents, No. 1,889,259, dated Nov. 29, 1932, and No. 1,977,078, dated Oct. 16, 1934. Also certain features of the switches herein disclosed are described and claimed in my prior application, Serial No. 233,828, filed Oct. 7, 1938, as will herein-after be pointed out.

Referring first to Figs. 1 to 6, inclusive, the numeral 20 designates a base or block of substantially rectangular contour molded from a suitable insulating material, such as "Bakelite." Base 20 is provided with a relatively large and relatively deep recess 21 opening to the upper surface thereof, the end walls of said recess being provided on the inner surfaces thereof with integral ribs or barriers 22 and 23 extending throughout the depth of the recess, wherefore the latter is of approximately H-shape when viewed from the top (see Fig. 2). Also formed integrally with the respective end walls of the recess and extending from the outer surfaces thereof respectively are barriers 24 and 25 which are interposed between the respective pairs of end wiring terminals of the switch, the lower 40 end portions of barriers 24 and 25 being cut away or angled inwardly toward the main body of base 20, as shown at 26 and 27 in Figs. 1 and 3, to minimize the amount of insulating material required to form base 20 and to reduce the weight of the latter.

Each end wall of the recess 21 is provided with a pair of like notches or grooves 28 (Fig. 2) opening to the upper surface of base 20. Notches 28 are structurally and functionally similar to the end wall notches shown in Figs. 7 and 8 of

my aforementioned application Serial No. 233,828. In the present switch, however, notches 28 open at the outer ends thereof to rectangular recesses 29 which open to the upper surface of base 20 and to the outer surfaces of the respective end walls. Recesses 29 are respectively adapted to accommodate, in a substantially flush relation to the upper surface of base 20 and in a substantially flush relation to the outer surfaces of the respective end walls, the flat rectangular outer end portions 30 of machined metal terminal members, the intermediate cylindrical portions 31 of which are accommodated by the notches 28. Said metal members are provided at the inner ends of portions 31 with reduced hollow cylindrical portions which penetrate correspondingly shaped openings in the relatively wide upper end portions 32 of like resilient stationary contacts 33, each of which is bent to the form best illustrated in Fig. 4, said reduced hollow cylindrical portions being upset over the upper end portions 32 of said contacts, as shown at 34, to rigidly and permanently unite said contact and terminal members.

The side walls 35 and 36 of base 20 are provided with auxiliary recesses 35^a and 36^a which are respectively opposed to and paired with the upwardly opening auxiliary recesses 22^a and 23^a in barriers 22 and 23 to accommodate the enlarged upper end portions 32 of contacts 33, said auxiliary recesses extending downwardly for only a portion of the depth of recess 21, as best illustrated in Fig. 4. When the contact and terminal members are in assembled position with respect to base 20 said enlarged end portions 32 of the contacts have their upper edges in a substantially flush relation to the upper surface of base 20 (see Fig. 4). In practice I prefer to bend the upper corners of enlarged portions 32 of the contacts 33 toward the portions 30 of their respective terminal members, as shown at 32^a in Figs. 2 and 4, to thereby provide for a resilient press fit of the contact and terminal units against the inner and outer surfaces of the end walls of recess 21. This arrangement has the effect of clamping the rectangular portions 30 of the terminal members against the inner walls of the respective recesses 29, thus insuring substantial sealing or dust-tightness of the end walls of the recess. The aforementioned press fit of these units with respect to base 20 further minimizes any tendency toward upward displacement of the units with respect to base 20 after complete assembly of the switch parts.

As best illustrated in Fig. 4, the longitudinally aligned contacts 33 extend downwardly from their terminal members in a relatively close but gradually spaced relationship to the opposed end walls of recess 21, the free end portions of said contacts being bent to conform to the junction between said end walls and the bottom wall 37 of said recess 21, the aforementioned gradual or increased spacing of said contacts being continued between said free end portions and said bottom wall 37, when all of the switch parts are in assembled relation. The free end portions of the longitudinally aligned contacts 33 terminate in downwardly bent or flared ends 33^a, which are substantially spaced longitudinally from each other. With reference to Fig. 4, it is to be understood that contacts 33 are bent in a manner to bias the free end portions thereof upwardly from the bottom wall 37 to a substantially greater extent than that shown, whereby said free end portions are placed under a predetermined

degree of compression or strain upon assembly of the parts in the manner illustrated.

Formed integrally with the bottom wall 37 of recess 21, and longitudinally aligned with the barriers 22 and 23, is a flat-topped rib or ridge 38 (Figs. 1 and 2) along which the bridging contactor carrying insulating plate 39 is adapted to slide. Plate 39 is preferably punched to the symmetrical form best illustrated in Fig. 5, the same having a centrally located elongated rectangular opening 40. A pair of notches 41 extends inwardly from each longitudinal edge of plate 39, said pairs of notches being aligned with each other and with opening 40. Each pair of notches 41 is adapted to freely accommodate, by end-wise insertion, a contactor 42 of the form best illustrated in Figs. 4 and 5. Each contactor 42 is provided with a flat lower portion 42^a adapted to underlie a portion 39^a of plate 39 formed by one of the pairs of notches 41, and the same is further provided with connecting portions 42^b divergently angled upwardly to the upper surface of plate 39, and with oppositely extending flat end portions 42^c, 42^c, which respectively overlie plate 39 at opposite sides of the notches 41. The angular bends in the contactors 42 cooperate with certain edges of the notches 41 as illustrated to insure against substantial displacement of said contactors longitudinally of plate 39.

The width of plate 39 is such that the side walls of recess 21 cooperate therewith to insure against lateral displacement of contactors 42 from the pairs of grooves, as best illustrated in Fig. 2. Plate 39 is provided at opposite ends thereof with relatively wide and relatively deep notches 43, 43 to provide suitable clearance between said plate and the barriers 22 and 23, pending engagement of the inner walls of said notches with the respective barriers to limit opposite movements of said plate. The extensions 44 thus provided at the four corners of the plate act to properly insulate the inactive lower stationary contact of such set, as best illustrated at the right-hand side of Fig. 4.

The side walls 35 and 36 of base 20 are provided at diagonally offset points thereof with upwardly opening notches 45 and 46 which are of identical form, and which are substantially like the notches 28 aforescribed. However, due to the relatively greater thickness of the side walls of base 20, as compared with the end walls thereof, the recesses 45^a and 46^a extend inwardly to a greater extent from the outer surface of the base than do the recesses 29 aforesaid. By this means I am able to employ for the upper pair of resilient contacts 47 (of identical form) terminal members having parts 30, 31 like those aforescribed. Each contact 47 has a substantially square upper end portion 47^a which is provided with an opening to accommodate the reduced cylindrical hollow end of the terminal member which is upset as shown at 34, for the purpose heretofore described. The upper corners 47^b of each contact portion 47^a are bent inwardly as shown to bind or clamp against the inner surfaces of the respective walls 35 and 36, whereby the flat rectangular portions 30 of said terminal members are drawn or clamped tightly against the inner walls of recesses 45^a and 46^a, to provide for substantial dust-tightness of said side walls and to resist any tendency toward accidental upward displacement of the upper set of combined contact and terminal members. The six wiring terminal members of the switch are

provided with tapped openings to receive the usual binding screws 30^a.

Each contact member 47 has a portion 47^c (Fig. 4) bent at substantially a right angle to portion 47^a to lie in a horizontal plane; the same being bent or reflexed as shown at 47^d to provide the portion 47^e which extends in a substantially horizontal plane throughout the major portion of the length of recess 21 when the switch parts are in assembled relation. As will be understood, portion 47^e before assembly thereof extends downwardly at a substantial angle to the horizontal, wherefore the same when assembled, as illustrated in Fig. 4, has a substantial degree of downward bias. Said portion 47^e is provided with a downwardly bent or bowed portion 47^f which is positioned at the mid-point of the length of recess 21, and which is adapted to be engaged by one or the other of the end portions 42^c of its associated contactor 42 when plate 39 is in one or the other of its extreme positions.

Thus as shown in Fig. 4, with plate 39 in its left-hand extreme position said portion 47^f of the upper contact will be engaged by the right-hand end portion 42^c of contactor 42, while the flat lower portion 42^a of said contactor is engaged with the left-hand lower contact of its associated set. Obviously upon movement to plate 39 to its right-hand extreme position the left-hand end portion of the contactor will be engaged with said portion 47^f and the flat lower portion 42^a of the contactor will be engaged with the right-hand contact 33. As will be understood, upon movement of carrier 39 from each extreme position to the other the portions 47^f of the upper contacts will be temporarily disengaged from their associated contactors 42 (during movement of portions 39^a of plate 39 in contact with said portions 47^f), thus providing a double break of the circuit between each upper contact 47 and that one of the lower set of associated contacts last connected therewith. It is to be understood that the contactor 42 and the associated contacts on the other side of rib 38 will function simultaneously in the same manner.

Each upper contact 47 is preferably extended horizontally beyond the portion 47^f thereof, as shown at 47^g; the primary purpose of which extensions is to provide a proper support for the relatively thin punched insulating plate 48 which is interposed between said upper contacts and the metal elements of the snap actuating means for the switch. Thus, as shown in Fig. 1, plate 48 is provided with a relatively long, narrow opening or slot 48^a to provide oscillating clearance for the vertical insulating plate 49, the tapered lower end 49^a of which is positioned within opening 40 in carrier plate 39 for driving the latter from one extreme position thereof to the other.

Plate 49 is pivotally supported by the connecting portion of a substantially U-shaped wire yoke member 50 (Fig. 1), the hooked ends of the arms of which are in turn pivotally engaged in openings provided in a stamped sheet metal top plate 55, in substantially the manner disclosed in my aforementioned Patent No. 1,977,078; and as more specifically shown in Figs. 1 to 3 of my aforementioned application, Serial No. 233,828. The actuating mechanism and superstructure of the switch herein disclosed are essentially like those shown in Figs. 1 to 3 of said application Serial No. 233,828; but the present switch embodies certain improvements in the structural details of said actuating mechanism and superstructure. That is to say, I provide a flat metal

top plate 52, with a flat rubber-like sheet or gasket 53 interposed between top plate 52 and the upper surface of base 20. I prefer to interpose between top plate 52 and gasket 53 a relatively thin flat sheet 54 of fiber or similar insulating material. The primary purpose of fiber sheet 54 is to prevent upward turning or bending of the opposite ends of gasket 53 as an incident to the compressive or clamping action of top plate 52 upon complete assembly of the switch parts. Although the size or length of top plate 52 might be increased to overcome the difficulty just mentioned, such a change would have the disadvantage of bringing the ends of top plate 52 relatively close to the wiring terminal members and screws 30^a associated therewith. Superimposed upon top plate 52 is a second top plate 55, within the centrally located dome-shaped portion 55^a of which the aforementioned yoke 50 is pivotally supported. Also supported by portion 55^a is a pin 56 which acts as a pivotal support for the operating lever 56^a, in the manner disclosed in said application Serial No. 233,828, portion 55^a having a relatively narrow slot 25 formed in the upper end thereof to provide oscillating clearance for said lever. Superimposed upon top plate 55 is an elastic, rubber-like member or gasket having a flat sheet or flange portion 57 which extends to a slight degree beyond plate 55, said gasket having a dome-shaped portion 57^a completely enclosing the aforementioned portion 55^a; but said portion 57^a is provided with a slit 57^b in the upper end thereof to permit oscillation of lever 56^a, although the walls of slit 57^b tend to close against each other and thereby closely hug said lever in all positions of the latter. With this arrangement substantial dust-tightness of the switch contacts and operating mechanism is insured under all conditions. Superimposed upon flange portion 57 is a metal plate 58 having an opening 58^a to accommodate the dome-shaped portion 57^a.

A pair of relatively long screws 59 extend upwardly through suitable passages in base 20 and through aligned openings in the aforementioned parts 53, 54, 52, 55, 57, 58, and freely through hollow metal spacers or ferrules 60, the threaded ends of which screws take into tapped openings in a suitable supporting plate 61 to rigidly clamp all of the aforementioned parts in assembled relation. The shanks of screws 59 preferably extend upwardly to a predetermined degree above plate 61, and said shanks are upset over the upper surface of said plate to retain the parts permanently in assembled relation. Plate 61 is provided adjacent opposite ends thereof with untapped openings 61^a, 61^b and with other openings 61^c, 61^d which are tapped, said sets of openings being adapted to provide alternative means for attaching the complete device to a suitable support.

As shown in Fig. 1 the vertical insulating actuating plate 49 is provided with a reduced substantially rectangular upper end portion 49^b 65 which telescopes into the lower end of the coiled compression spring 62. Telescoped onto the upper end of spring 62 is an approximately inverted cup-shaped sheet metal member 63, the closed upper end 63^a of which is dished or depressed to provide a suitable abutment for the rounded lower end 58^b of lever 56^a. In practice member 63 is formed to the shape thereof illustrated from an elongated strip or plate of metal of a width slightly less than the diameter of said member, as measured across the downwardly

extending arm portions 63^b and 63^c thereof which are of arcuate form in transverse cross section.

By the arrangement illustrated, the upper end of member 63 is of a width less than its full diameter at the sides thereof adjacent to the arms of yoke member 50, with the resultant formation of slots at such sides throughout the length or depth thereof, as indicated at 63^d, whereby adequate clearance between member 63 and the arms of yoke member 50 is insured. Member 63 is made of a length substantially less than the normal length of spring 62 when the latter is in the assembled position thereof illustrated. I thereby insure against interference between the arms 63^b and 63^c of member 63 and the shoulders formed on the insulating actuator 49 during operation of the switch mechanism.

As shown in Figs. 1 and 2 said rib 38 is provided with a recess 38^a having an arcuate bottom wall, to provide clearance for the lower end 49^a of insulating actuator 49.

The bottom wall 37 of recess 21 is preferably provided with a pair of substantially rectangular recesses respectively arranged on opposite sides of rib 38, one of said recesses being shown at 64 in Fig. 4. The primary purpose of recesses such as 64 is to provide adequate creepage space between the adjacent ends of the longitudinally aligned sets of lower contacts to avoid the likelihood of creating a conducting path therebetween as an incident to deposit of metal particles worn from the switch contacts and contactors. However, if desired each recess 64 may have positioned therein a substantially rectangular block or plate of fiber or other suitable arc resistant insulating material as shown at 65 in Fig. 4, thus not only increasing the length of the creepage path, but likewise acting to cool and snuff any arcs drawn between each contactor and its associated set of lower contacts, while protecting the bottom wall of said recess from the charring effect of such arcs.

Due to the aforesigned relatively greater depth of the recesses 45^a and 46^a associated with the side wall notches 45 and 46, I prefer to provide in the outer surfaces of said side walls grooves to at least partially accommodate the respective wires extending from the side wall terminal members, one of said grooves being shown at 46^b in Fig. 6. As shown in Fig. 3 the lower portions of the exterior surfaces of the side walls of base 20 are angled inwardly to a slight degree, as indicated at 20^a and 20^b.

With the switch parts in the relative positions thereof illustrated in Figs. 1 and 2 it is to be understood that each of the contactors will provide an electrical connection between one of the side wall terminals and one of the left-hand end wall terminals at the corresponding side of rib 38; whereas upon movement of plate 39 to its opposite extreme position said side wall terminals will be electrically connected by the respective contactors with the right-hand end wall terminals at the respectively corresponding sides of rib 38.

The manner of effecting snap movement of plate 39 from each extreme position thereof to the other is believed to be obvious. It may be pointed out, however, that upon movement of lever 56^a from left to right (Fig. 1) the lower end 56^b thereof acts upon member 63 to further compress spring 62 to effect storage of the required amount of energy in the latter. The movement of member 63 toward the left causes the lower end 49^a of actuating plate 49 to move toward

the right to take up the lost motion between the latter and the right hand end wall of slot 40 in carrier plate 39. When the lower end 56^b of said lever passes to the left beyond a line vertical to the instant point of pivotal support of actuating plate 49 by yoke 50, the stored energy in spring 62 is released to effect snap movement of yoke 50, plate 49 and carrier 39 to the right-hand extreme positions thereof. A similar snap action of said parts toward the left likewise results upon a predetermined degree of movement of lever 56^a toward the left-hand extreme position thereof illustrated.

As will be apparent only two forms of contact and terminal units are required to provide the double-pole, double-throw snap switch aforesigned; namely, the two like upper units and the four like lower units. When the parts are completely assembled as shown in Fig. 1 all of said units are positively and permanently retained in proper relation to each other and to base 20 and to the other parts of the switch. Although the terminal members are located in a convenient position for wiring, at the upper end 20 of base 20, they are properly insulated from the top plates and other elements of the switch superstructure.

In Figs. 7 and 8 I have shown a modification wherein slightly different forms of upper and lower contacts and contactors and the carrier for the latter are employed, the other parts of the switch including base 20 preferably being identical with the corresponding parts aforesigned. Thus the terminal members having portions 39, 31, 34 and associated screws 30^a are attached to base 20 in the manner aforesigned. The four lower contacts 66 (of which two are shown in Fig. 7) have their enlarged and perforated upper ends rigidly attached to the respective terminal members and positioned with their upper edges in a plane substantially flush with the upper surface of base 20. The free ends of contacts 66 extend downwardly along the respective end walls of recess 21 and thence along the bottom wall 37 of said recess in gradually increasing spaced relationship to the latter. The free ends or tips 66^a of said contacts overlie, to a slight extent, the aforesigned recesses 64 in the bottom wall 37 and are bent or flared downwardly toward said recesses, as shown. Contacts 66 are initially formed in a manner to bias the free ends thereof upwardly from the positions thereof illustrated, in which latter positions the same are maintained under a predetermined degree of strain or compression by the other cooperating parts of the switch.

The insulating carrier plate 67 is notched at its ends, as shown at 67^a, 67^c, to provide adequate clearance between said plate and the end wall barriers aforesigned during movement of said plate to its respective extreme positions. Plate 67 is provided centrally thereof with an opening 67^b corresponding with the opening 40 in plate 39 and having a like function. Substantially rectangular notches 67^c, 67^e are provided in the side edges of plate 67 in alignment with opening 67^b; and each notch is adapted to freely accommodate the substantially U-shaped portion 68^a of a contactor the ends 68^b and 68^c of which are bent to extend flatwise to overlie plate 67 at opposite sides of the notch 67^c associated therewith. As best illustrated in Fig. 7, said U-shaped portions of the contactors extend slightly below the lower surface of plate 67, thus further de-

pressing the lower contacts 66 with which they happen to be engaged.

Each of the two upper stationary contacts comprises a vertical portion 69^a rigidly attached to its associated terminal member as by means of the upset portion or flange 34; a portion 69^b bent laterally at a right angle to portion 69^a to lie in a substantially horizontal plane; a bend or reflex 69^c; and a relatively long contact portion 69^d, the free end of which is flared or bent upwardly to a slight extent, as shown at 69^e. As will be understood each upper contact is initially formed to provide for extension of portion 69^d thereof downwardly to a substantial degree with respect to the horizontal, whereby said portion 69^d is placed under a predetermined stress or strain when the parts are in assembled relation.

The arrangement is such that the portions 68^b, 68^c of each contactor are continuously engaged by the portion 69^d of the upper contact associated therewith; whereas the lower ends of the U-shaped portions 68^a of said contactors are adapted to engage alternately the longitudinally alined contacts 66, 66 of each set. The electrical functions of the switch of Figs. 7 and 8 are substantially identical with those of the switch first described. The portions 69^d of the upper contacts are preferably of the length shown to provide a proper support for the fiber plate 48, the function of which was heretofore described. The extensions 67^d at the four corners of plate 67 are preferably made rather short, to avoid any possible interference between the same and the lower contacts 66; while insuring overlapping of portions of contacts 66 by said plate in all positions of the latter, as illustrated in Fig. 7.

What I claim as new and desire to secure by Letters Patent is:

1. In a double-pole, double-throw snap switch without an off position, in combination, an insulating base having a recess formed therein and opening to the upper surface thereof, a rib formed integrally with the bottom wall of said recess and having a flat upper surface, an insulating plate slidable flatwise upon said upper surface of the rib, a pair of lower contacts respectively secured to the opposite ends of said recess and having resilient free end portions spaced from each other longitudinally of said recess and biased upwardly beyond said flat surface of the rib, an upper contact secured to a side wall of said recess and having a resilient free end portion biased downwardly toward said flat surface of the rib, said plate in all positions thereof being interposed between said upper contact and said lower contacts to maintain the same in substantially parallel spaced relation, a contactor carried by said plate and having portions exposed at the upper and lower surfaces of the latter, said upper exposed portion of said contactor being engaged with the resilient portion of said upper contact in each extreme position of said plate, said lower exposed portion of said contactor being engaged with the resilient portions of said lower contacts alternately upon movement of said plate to opposite extreme positions respectively, and manually operable means including means for effecting snap movement of said plate from each extreme position thereof to the other.

2. In a double-pole, double-throw snap switch without an off position, in combination, an insulating base having a recess formed therein and opening to the upper surface thereof, a rib formed integrally with the bottom wall of said

recess and having a flat upper surface, an insulating plate slidable flatwise upon said upper surface of the rib, four resilient contacts secured to the opposite ends of said recess and arranged in longitudinally spaced alined pairs, the free end portions of said contacts being normally biased above the upper surface of said rib, two additional resilient contacts secured to the respective side walls of said recess in diagonally opposed relationship to each other and having free end portions overlapping and biased downwardly toward the respective longitudinally alined pairs of free end portions aforementioned, said plate in all positions thereof being interposed between the free end portions of each of said additional contacts and the respective longitudinally alined pairs of free end portions to maintain the same in substantially parallel spaced relation, a pair of contactors carried by said plate and having portions thereof exposed at the upper and lower surfaces of the latter, the upper exposed portions of said contactors being engaged with the free end portions of the respective additional contacts in each extreme position of said plate, the lower exposed portions of said contactors being engaged alternately with the longitudinally alined free end portions of said first mentioned pairs upon movement of said plate to opposite extreme positions respectively, and manually operable means including means for effecting snap movement of said plate from each extreme position thereof to the other.

3. In a double-pole, double-throw snap switch without an off position, in combination, an insulating base having a recess formed therein and opening to the upper surface thereof, a rib formed integrally with the bottom wall of said recess and having a flat upper surface, an insulating plate slidable flatwise upon said upper surface of the rib, four resilient contacts secured to the opposite ends of said recess and arranged in longitudinally spaced alined pairs, the free end portions of said contacts being normally biased above the upper surface of said rib, two additional resilient contacts secured to the respective side walls of said recess in diagonally opposed relationship to each other and having free end portions overlapping and biased downwardly toward the respective longitudinally alined pairs of free end portions aforementioned, said plate in all positions thereof being interposed between the free end portions of each of said additional contacts and the respective longitudinally alined pairs of free end portions to maintain the same in substantially parallel spaced relation, a pair of contactors carried by said plate and having portions thereof exposed at the upper and lower surfaces of the latter, the upper exposed portions of said contactors being engaged with the free end portions of the respective additional contacts in each extreme position of said plate, the lower exposed portions of said contactors being engaged alternately with the longitudinally alined free end portions of said first mentioned pairs upon movement of said plate to opposite extreme positions respectively, and manually operable means including means for effecting snap movement of said plate from each extreme position thereof to the other, said last mentioned means including a metal yoke member pivotally supported relatively to said base and depending into said recess, a flat insulating plate pivotally supported by said yoke and spring biased with the latter to one extreme position or the other, said last mentioned insulating plate

having a lost motion driving connection with said insulating plate first mentioned, and a relatively thin flat insulating plate interposed between the free end portions of all of said contacts and said yoke member, said last mentioned plate having a slot formed therein to provide clearance for said insulating plate second mentioned.

4. In an electric snap switch, in combination, a substantially rectangular molded insulating base of greater length than width having a recess of corresponding shape formed therein and opening to the upper surface thereof, aligned ribs formed integrally with the bottom and end walls of said recess and arranged in the plane of the longitudinal center line of said base, said bottom wall rib having a flat upper surface, a flat punched plate of insulating material slidable upon said last mentioned rib into abutting engagement with said end wall ribs alternately, a pair of stamped sheet metal bridging contactors carried by said plate on opposite sides of said bottom wall rib, each contactor having an intermediate portion thereof exposed on the lower surface of said plate at the transverse center line of the latter, each contactor also having oppositely extending end portions thereof exposed on the upper surface of said plate in spaced relation to said transverse center line of the latter, four like combined contact and terminal members secured to the end walls of said recess in substantially flush relation to the upper surface of said base, said members having resilient free end portions arranged in longitudinally spaced and aligned pairs adjacent to the bottom wall of said recess but normally biased above the upper surface of said bottom wall rib, an additional pair of like combined contact and terminal members secured to the respective side walls of said recess in substantially flush relation to the upper surface of said base in diagonally opposed relationship to each other, said last mentioned members having resilient free end portions extending in opposite directions respectively across the transverse center line of said recess and adapted for engagement with at least one of the oppositely extending end portions of each contactor in each extreme position of said plate, a flat insulating plate having a lost motion driving connection with said plate first mentioned, and manually operable snap action mechanism for effecting movement of said second plate from each extreme position thereof to the other.

5. In a double-pole, double-throw snap switch, in combination, a molded insulating base of substantially rectangular contour, said base having a recess formed therein and opening to the upper surface thereof, a rib formed integrally with said base and having a flat surface offset upwardly from the bottom wall of said recess, a plate of insulating material positioned within said recess and slideable flatwise upon said surface of the rib, two sets of lower longitudinally aligned resilient contacts secured to the end walls of said recess and having the free end portions thereof normally biased toward a plane above said flat surface of said rib, the free end portions of each set of contacts being substantially spaced from each other longitudinally of the base, a pair of upper contacts respectively secured to the side walls of said recess, said last mentioned contacts each having a resilient arm biased toward said flat surface of the rib and overlying the free end portions of one of said sets of contacts, a pair of stamped sheet metal contactors carried by said

plate, each contactor having a portion thereof exposed at the lower surface of said plate and adapted for engagement with said longitudinally aligned contacts alternately upon movement of said plate to opposite extreme positions respectively, each contactor also having a portion thereof exposed at the upper surface of said plate and adapted for engagement with its associated upper contact in each extreme position of said plate, and manually operable means associated with said plate to effect snap movement thereof from each extreme position to the other.

6. In a two-position double-pole, double-throw snap switch of the tool-handle type, in combination, a molded insulating base having a relatively long substantially rectangular recess formed therein and opening to the upper surface thereof, the end walls and side walls of said recess having six substantially similar sets of notches and recesses formed therein and opening to the upper surface of said base, said end walls each having two of said sets of notches and recesses and said side walls each having one of said sets of notches and recesses arranged in diagonally opposed relationship to each other, six like terminal members positioned within said sets of notches and recesses in substantially flush relationship to the upper surface of said base, four like resilient contact members rigidly attached to the respective end wall terminal members and having the free end portions thereof arranged in longitudinally spaced and aligned pairs adjacent to but biased upwardly from the bottom wall of said recess, a flat insulating plate superimposed upon said free end portions of said contacts and adapted to overlap all of the latter in all positions of the former, a pair of metal contactors carried by said plate and adapted to alternately engage the respective free end portions of said longitudinally aligned pairs upon movement of said plate to opposite extreme positions, two like but reversely arranged resilient contact members rigidly attached to the respective side wall terminal members and having the free end portions thereof overlying said plate in all positions of the latter, said contactors being also respectively engaged with one of said last mentioned free end portions in each extreme position of said plate, and manually operable means including means for effecting snap movement of said plate from each extreme position thereof to the other.

7. In a two-position double-pole, double-throw switch of the tool-handle type, in combination, a molded insulating base having a relatively long substantially rectangular recess formed therein and opening to the upper surface thereof, the end walls and side walls of said recess having six substantially similar sets of notches and recesses formed therein and opening to the upper surface of said base, said end walls each having two of said sets of notches and recesses and said side walls each having one of said sets of notches and recesses arranged in diagonally opposed relationship to each other, six like terminal members positioned within said sets of notches and recesses in substantially flush relationship to the upper surface of said base, four like resilient contact members rigidly attached to the respective end wall terminal members and having the free end portions thereof arranged in longitudinally spaced and aligned pairs adjacent to but biased upwardly from the bottom wall of said recess, a flat insulating plate superimposed upon free end portions of said contacts and adapted to overlap all of the latter

in all positions of the former, a pair of metal contactors carried by said plate and adapted to alternately engage the respective free end portions of said longitudinally alined pairs upon movement of said plate to opposite extreme positions, two like but reversely arranged resilient contact members rigidly attached to the respective side wall terminal members and having the free end portions thereof overlying said plate in all positions of the latter, said contactors being also respectively engaged with one of said last mentioned free end portions in each extreme position of said plate, means including a metal top plate secured to the upper surface of said base to retain all of said wiring terminal members in assembled position, a flexible, rubber-like sheet interposed between said top plate and the upper surface of said base to insulate said terminal members and to provide for substantial dust-tightness of the peripheral wall of said recess, snap acting mechanism for said plate including a manually operable lever, a substantially dome-shaped member of flexible, rubber-like material overlying the base recess to provide for substantial dust-tightness of the upper end of the latter, said dome-shaped member having a slit formed therein to accommodate said lever and to provide for oscillation of the latter while substantially insuring against ingress of dust to said recess, said mechanism being adapted to effect snap movement of said plate from each extreme position thereof to the other upon movement of said lever in a corresponding direction.

8. In an electric snap switch of the character described, in combination, an insulating base having a recess opening to the upper surface thereof, four like combined resilient contact and terminal members secured in pairs to the opposed end walls of said recess in a substantially flush relationship to the upper surface of said base, the resilient contact portions of all of said members extending downwardly along the respective end walls and then along the bottom wall of said recess to provide spaced longitudinally alined pairs normally biased upwardly from said bottom wall, two additional like combined resilient contact and terminal members secured in reverse relationship to each other at diagonally opposite points on the respective side walls of said recess in a substantially flush relationship to the upper surface of said base, the resilient contacts of said last mentioned members each having a portion extending downwardly along its associated side wall of the recess and a metal strip portion bent laterally at substantially a right angle to said wall, said metal strip portion being bent to reflex form whereby the free end portion extends longitudinally of said recess to opposite sides of the transverse center line of the latter, a flat punched plate of insulating material positioned below the resilient free end portions of said last mentioned pair of members and above the free end portions of said four members first mentioned and interposed between said free end portions in all positions of said plate, a pair of bridging contactors carried by said plate and adapted for engagement with said upper pair of free end portions in each extreme position of said plate, said contactors being also adapted to engage two of the lower resilient contact portions at one side or the other of the transverse center line of said recess in each extreme position of said plate, manually operable means for effecting snap movement of said plate from each extreme position thereof to the other, each of said upper pair of free end portions having a downwardly extending boss or bend formed therein in alinement with the transverse center line of said recess, and said plate having an integral portion thereof interposed between spaced exposed portions of each contactor at the upper surface of said plate, to thereby provide for a double break between each contactor and the resilient free end portions of the contacts associated therewith upon each movement of said plate from one extreme position to the other.

9. In an electric snap switch of the character described, in combination, an insulating base having a recess opening to the upper surface thereof, four like combined resilient contact and terminal members secured in pairs to the opposed end walls of said recess in a substantially flush relationship to the upper surface of said base, the resilient contact portions of said members extending downwardly along the respective end walls and then along the bottom wall of said recess to provide spaced longitudinally alined pairs normally biased upwardly from said bottom wall, two additional like combined resilient contact and terminal members secured in reverse relationship to each other at diagonally opposite points on the respective side walls of said recess in a substantially flush relationship to the upper surface of said base, the resilient contacts of said last mentioned members each having a portion extending downwardly along its associated side wall of the recess and a metal strip portion bent laterally at substantially a right angle to said wall, said metal strip portion being bent to reflex form whereby the free end portion extends longitudinally of said recess to opposite sides of the transverse center line of the latter, a flat punched plate of insulating material positioned below the resilient free end portions of said last mentioned pair of members and above the free end portions of said four members first mentioned and interposed between said free end portions in all positions of said plate, a pair of bridging contactors carried by said plate and adapted for engagement with said upper pair of free end portions in each extreme position of said plate, said contactors being also adapted to engage two of the lower resilient contact portions at one side or the other of the transverse center line of said recess in each extreme position of said plate, manually operable means for effecting snap movement of said plate from each extreme position thereof to the other, each of said upper pair of free end portions having a downwardly extending boss or bend formed therein in alinement with the transverse center line of said recess, and said plate having an integral portion thereof interposed between spaced exposed portions of each contactor at the upper surface of said plate, to thereby provide for a double break between each contactor and the resilient free end portions of the contacts associated therewith upon each movement of said plate from one extreme position to the other.

10. As an article of manufacture, a common combined resilient contact and wiring terminal member for a snap switch of the double-throw type without an off position, said member comprising a machined metal element having a substantially square outer flange, a substantially cylindrical intermediate portion and an inner cylindrical portion of relatively smaller diameter than said intermediate portion, said element having a centrally located tapped opening formed therein to accommodate the shank of a binding screw, a resilient contact element having a perforated square portion alined with said flange and rigidly secured to said machined metal element by upsetting the end of said inner cylindrical portion thereover, said contact element having an integral metal strip portion bent at substantially a right angle to said square portion, said metal strip portion being bent to re-

flexed form to provide a relatively long free end portion which is initially bent and normally biased by its own resiliency downwardly at an angle to the horizontal, said free end portion being adapted upon assembly thereof with respect to other parts of the switch to be maintained in a substantially horizontal plane against said downward bias.

11. As an article of manufacture, a common combined resilient contact and wiring terminal member for a snap switch of the double-throw type without an off position, said member comprising a machined metal element having a substantially square outer flange, a substantially cylindrical intermediate portion and an inner cylindrical portion of relatively smaller diameter than said intermediate portion, said element having a centrally located tapped opening formed therein to accommodate the shank of a binding screw, a resilient contact element having a perforated square portion alined with said flange and rigidly secured to said machined metal element by upsetting the end of said inner cylindrical portion thereover, said contact element having an integral metal strip portion bent at substantially a right angle to said square portion, said metal strip portion being bent to reflexed form to provide a relatively long free end portion which is initially bent and normally biased by its own resiliency downwardly at an angle to the horizontal, said free end portion being adapted upon assembly thereof with respect to other parts of the switch to be maintained in a substantially horizontal plane against said downward bias, and said relatively long free end portion having a downward bend or boss formed at substantially the mid-point of its length, for the purpose set forth.

12. In an electric snap switch, in combination, a molded insulating base having a recess formed therein and opening to the upper surface thereof, a wall of said recess having a notch and an alined auxiliary recess formed therein and opening to the upper surface of said base, said notch opening to the inner surface of said wall and to said auxiliary recess and said auxiliary recess opening to the outer surface of said wall, a machined metal terminal member having an outer substantially square flange portion adapted to fit into said auxiliary recess in a relation substantially flush with the upper surface of said base, said member having an intermediate substantially cylindrical portion adapted to seat within said notch and an inner substantially cylindrical portion of relatively smaller diameter, said terminal member having a tapped opening extending centrally therethrough to accommodate the shank of a binding screw, a resilient contact member having a substantially square upper end portion of a size corresponding to said flange portion, said upper end portion having an opening to accommodate said inner cylindrical portion and the latter having its inner end upset over said upper end portion to rigidly and permanently secure said parts to each other, the corners of said upper end portion being bent to a substantial degree toward said flange portion to provide for a resilient press fit of said unit against opposite faces of said recess to thereby provide a substantially dust-tight lateral seal for said notch, said contact member having a free end portion adapted for cooperation with a contactor of suitable form.

13. In an electric snap switch of the tool-handle type, in combination, a molded base of

phenolic condensation type material having a substantially rectangular recess formed therein and opening to the upper surface thereof, a rib formed integrally with said base and having a flat surface offset upwardly from the bottom wall of said recess, a flat plate of insulating material slidable upon said flat surface, a contactor carried by said plate at one side of said rib and having portions thereof exposed at the lower and upper surfaces of said plate, a pair of lower and upper resilient contacts between which said plate is continuously interposed, said contactor being movable by said plate into and out of bridging engagement with said resilient contacts, a separately formed fiber block of rectangular contour carried by said base at a point closely adjacent to the free end of said lower contact and over which said contactor is adapted to move when disengaged from said lower contact, said block being adapted to assist in cooling and snuffing any arcs drawn between said lower contact and said contactor upon separating movement of the latter and to protect the bottom wall of said recess from the charring effect of such arcs, and manually operable means associated with said base to effect snap movements of said plate and said contactor from each extreme position thereof to the other.

14. In an electric snap switch of the tool-handle type, in combination, a molded insulating base subject to charring under the heat of an electric arc, said base having a substantially rectangular recess formed therein and opening to the upper surface thereof, a rib formed integrally with said base and having a flat surface offset upwardly from the bottom wall of said recess, a flat plate of insulating material slidable upon said flat surface, a contactor carried by said plate at one side of said rib and having portions thereof exposed at the lower and upper surfaces of said plate, a pair of lower and upper resilient contacts between which said plate is continuously interposed, said contactor being movable by said plate into and out of bridging engagement with said resilient contacts, a separately formed block of arc resistant insulating material of substantially rectangular contour carried by said base at a point closely adjacent to the free end of said lower contact and over which said contactor is adapted to move when disengaged from said lower contact, said block being adapted to assist in cooling and snuffing any arcs drawn between said lower contact and said contactor upon separating movement of the latter and to protect the bottom wall of said recess from the charring effect of such arcs, and manually operable means associated with said base to effect snap movements of said plate and said contactor from each extreme position thereof to the other.

15. In a double-pole, double-throw snap switch, in combination, an insulating base having a recess formed therein and opening to the upper surface thereof, an insulating plate slidable in a plane parallel to the bottom wall of said recess, a pair of contacts secured to the opposite end walls of said recess and having resilient free end portions spaced from each other longitudinally of said recess, a third contact secured to a side wall of said recess and having a resilient free end portion, said plate in all positions thereof being interposed between said third contact and said contacts first mentioned, a punched and stamped sheet metal contactor carried by said plate and having portions thereof exposed at opposite surfaces of the latter, one exposed portion of said

contactor being engaged with the resilient portion of said third contact in each extreme position of said plate, the other exposed portion of said contactor being engaged with the resilient portions of said contacts first mentioned alternately upon movement of said plate to opposite extreme positions respectively, and manually operable means including means for effecting snap movement of said plate in opposite directions respectively from each extreme position thereof to the other.

16. In a double-pole, double-throw snap switch, in combination, an insulating base having a recess formed therein and opening to the upper surface thereof, an insulating plate slidable in a plane parallel to the bottom wall of said recess, a pair of lower contacts secured to the opposite end walls of said recess and having resilient free end portions spaced from each other longitudinally of said recess, an upper contact secured to a side wall of said recess and having a resilient free end portion, said plate in all positions thereof being interposed between said upper contact and said lower contacts, a stamped sheet metal contactor carried by said plate and having portions exposed at the upper and lower surfaces of the latter, said upper exposed portion of said contactor being engaged with the resilient portion of said upper contact in each extreme position of said plate, said lower exposed portion of said contactor being engaged with the resilient portions of said lower contacts alternately upon movement of said plate to opposite extreme po-

sitions respectively, and manually operable means including means for effecting snap movement of said plate in opposite directions respectively.

17. In a double-pole, double-throw snap switch, 5 in combination, a molded insulating base having a recess formed therein and opening to the upper surface thereof, a flat punched insulating plate slidable in a plane parallel to the bottom wall of said recess, a pair of lower contacts respectively secured to the opposite end walls of said recess and having resilient free end portions spaced from each other longitudinally of said recess and biased upwardly from the bottom wall of the latter, an upper contact secured to a side wall of 10 said recess and having a resilient free end portion biased toward said bottom wall of the recess, said plate in all positions thereof being interposed between said upper contact and said lower contacts, a stamped sheet metal contactor carried by said plate and having portions exposed 15 at the upper and lower surfaces of the latter, said upper exposed portion of said contactor being engaged with the resilient portion of said upper contact in each extreme position of said plate, said lower exposed portion of said contactor being engaged with the resilient portions of said lower contacts alternately upon movement of said plate to opposite extreme positions respectively, and manually operable means including means for effecting snap movement of said plate in opposite directions to said opposite extreme positions respectively.

GEORGE J. MEUER.
